UNITED STATES PATENT OFFICE.

EDGAR GRANVILLE XANDER, OF MANSFIELD, OHIO.

GARBAGE-RECEPTACLE.

SPECIFICATION forming part of Letters Patent No. 357,258, dated February 8, 1887.

Application filed August 19, 1886. Serial No. 211,259. (No model.)

To all whom it may concern:

Be it known that I, EDGAR GRANVILLE XANDER, a citizen of the United States, residing at Mansfield, in the county of Richland and State of Ohio, have invented certain new and useful Improvements in Garbage-Receptacles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to produce an air-tight garbage-receptacle which may receive the material at the house, be conveniently handled, and easily transported, an empty receptacle being exchanged for a full one. This will render unnecessary any change at the house from a sink to a transportable receptacle, and the consequently unhealthy pollution of the air.

Figure 1 of the drawings is a plan view of the garbage-receptacle fastened so as to be air-tight. Fig. 2 is a vertical section with the clamp-lever turned so that the lid is locked in place, and Fig. 3 is a perspective view of the cover.

30 In the drawings, A represents my garbage-receptacle, which consists of the staves *a*, surrounded by, preferably, eight iron hoops, B B', the fourth hoop B' being made much larger and heavier than the others, so as to rest behind the wagon sand-boards when tipping it on the wagon, and to afford a hold for the wagoner when putting it on and taking it off the wagon.

C is the lid or cover, which fits inside the

staves, formed of crossed boards, and is provided with the annular packing *c* on its edge to insure air-tightness. On top and in the center of the cover I pivot a diametrical bar, D, on the screw E, whose head is on the under side, and whose threaded upper end is provided 40 with a nut, E'. At equal distances from the center of cover the bar D has an open cross-slot, *d*, the openings being in reverse directions. Diametrically opposite to each other are arranged the screw-bolts F F', whose threaded 45 ends project above the barrel and are provided with nuts G, and, if desired, with the washers H. The lower end of these screw-bolts is flattened, so as to project at right angles to the shank on both sides, and thus form 50 a T-bolt. In each arm *f* is made a bolt-hole, *f'*, through which passes a bolt, I, from the inside of barrel, where its head is, and on the end is a nut, J.

Having thus described all that is necessary 60 to a full understanding of my invention, what I claim as new, and desire to protect by Letters Patent, is—

The combination, with a garbage-receptacle and its cover, of the bar D, centrally pivoted 65 on the lid and open-slotted at *d d* in opposite directions, the receptacle being provided with the diametrically-opposite screw-bolts F F' and nuts G G, whereby the nuts may be loosened, the bar turned, and the cover lifted or removed, as set forth.

In testimony whereof I affix my signature in presence of two witnesses.

EDGAR GRANVILLE XANDER.
